CLAIM

The ornamental design for a wheel rim for vehicle as shown and described.

DESCRIPTION

FIG. 1 is a front perspective view of the wheel rim for vehicle showing my design;

FIG. 2 is a front elevation view thereof;

FIG. 3 is a left side view thereof;

FIG. 4 is a right side view thereof;

FIG. 5 is a top plan view thereof; and,

FIG. 6 is a bottom view thereof.

Portions of the wheel rim for vehicle shown in broken lines form no part of the claimed design.

1 Claim, 6 Drawing Sheets
